(57) **CLAIM**

The ornamental design for a chair frame, as shown and described.

DESCRIPTION

FIG. 1 is a perspective view of a chair frame in accordance with a preferred embodiment of the present invention; FIG. 2 is a front view of the chair frame shown in FIG. 1; FIG. 3 is a back view of the chair frame shown in FIG. 1; FIG. 4 is a left side view of the chair frame shown in FIG. 1, with the right side being a mirror image thereof; FIG. 5 is a top view of the chair frame shown in FIG. 1; and, FIG. 6 is a bottom view of the chair frame shown in FIG. 1. The broken lines shown in the drawings are for illustrative purposes only and form no part of the claimed design.
